ADJUSTABLE CORD LOCK

Julius Nisenson, Brooklyn, N. Y.

Application April 19, 1937, Serial No. 137,679

12 Claims. (Cl. 156—17)

This invention relates generally to Venetian blinds and more particularly to an adjustable cord lock for use in conjunction with slat elevating or lowering cords as commonly used with 5 said blinds.

The present invention to be hereinafter described is suitable for use in conjunction with all types of Venetian blind head-bars or head-piece casings using similar cord arrangements for 10 elevating and lowering the Venetian blind slats. This invention is particularly suited for use in conjunction with a cord lock such as that described in Patent Number 2,036,231 granted to me April 7, 1936 to which reference may be had. 15 With this in view, only the principal features of the invention are illustrated and described, as it will be understood by those skilled in the art that the same may be readily adapted to other Venetian blind head-bars or head-piece casings.

Heretofore in Venetian blind head-bars or head-piece casings which are of uniform construction, and are manufactured as a unit having standard settings so that large scale production may be used to advantage, difficulty has been 20 encountered with the cord locks thereon because different sizes and numbers of slats have resulted in different weights with resultant differences in tension on the elevating and lowering cords. Variation in tension changes the diameter of the 25 cords so that a fixed unadjustable setting for a light weight blind will allow a heavy weight blind to slip and conversely if the setting of the cord lock is unadjustably fixed in a position for use with a heavy blind, the cord lock will take hold too easily and difficulty will be encountered in lowering the slats.

Among the objects of this invention is the provision of novel structure for the accurate and 40 easy control of the cord lock or cord brake, which coacts with the cords for elevating or lowering the slats of a Venetian blind.

Another object herein is the provision of structure which is easily installed on the head-bar or 45 head-piece casing and is readily adapted to head-bars or head-piece casings now in use.

A further object herein is the provision of an 50 adjustable cord lock which is easily adjusted without the use of special tools after the Venetian blind has been actually installed. The adjustment is thus made under actual operating conditions, so that an accurate adjustment setting is obtained, and such setting is permanently 55 maintained until readjustment is made.

A feature of the invention lies in the fact that 60 since the adjustment thereof may be made without disturbing any other adjustments which may be part of the Venetian blind mechanism with which this invention is included, adjustments

may be readily made from time to time to allow for wear of the cords or other related elements.

Another feature of this invention permits very fine adjustment of the cord brake or lock so that a high degree of sensitivity is provided which is 5 of special value where the lateral movement of the cords is restricted as will be more fully explained below.

A still further advantage of the present construction resides in the simplicity in manufacture and assembly with consequent economy. 10

These objects, further features, incidental ends and advantages will more fully appear in the 15 progress of this disclosure and as pointed out in the appended claims.

In the accompanying drawing, similar reference characters designate corresponding parts throughout the several views in which:

Figure 1 is a fragmentary perspective view looking into a head-piece casing at one end thereof, 20 showing an embodiment of the invention.

Figure 2 is a partial vertical longitudinal sectional view of Figure 1 taken along the plane 2—2 thereon.

Figure 3 is a partial perspective fragmentary 25 view of the cord lock assembly frame with the dog, roller, and adjuster removed.

Figure 4 is a bottom plan view of Figure 3 with the cord separator removed.

Figure 5 is a perspective view of the dog and 30 pintle.

Numerical 10 indicates a Venetian blind head-piece casing having a rearwardly bent front flange 11, a forwardly bent rear flange 12; a front wall 13; a rear wall 14; a bottom wall 15; and 35 a reinforcing tie-bar 16.

Manual control cords 17 and 18 pass upwardly through an opening (not shown) in the bottom wall 15, through an orifice 19 in the assembly frame indicated generally by numeral 20, over the 40 roller 21 and thence to any suitable slat elevating or lowering means known in the art as will cause the cords to be under tension caused by the weight of the slats. Such means ordinarily include rollers, set at suitable points in the bottom wall 15, over which the cords pass to travel 45 downwardly through orifices in said wall and to terminate in a weight bar adapted to raise the slats above it when the same is raised. This construction is well known in the art and for this reason is not illustrated in the drawing.

An outer right angle plate 22 includes a vertical portion 23 and a horizontal base 24. Vertical portion 23 is provided with orifices 25 and 55 26, while base 24 is provided with a relatively large opening 27, having an indentation 28 at one margin thereof and another indentation 29 in an opposite margin thereof. Base 24 is further provided with an orifice 30 and an elongated ori- 60

fice or guideway 31. The inner end of the indentation 29 is provided with a widened portion 32.

An inner right angle plate 33 includes a vertical portion 34 and a pair of horizontal legs 35 and 36. Portion 34 is provided with orifices 37 and 38 and leg 35 is provided with an orifice 39. The inner and upper end of portion 34 is bent rearwardly at 40 in order to avoid abrading the cord 18.

- 10 The plate 33 is placed upon the plate 22 in the manner illustrated in Figure 3 of the accompanying drawing and the legs 35 and 36 are affixed to the base 24 preferably by spot welding, thereby forming the frame 20. Orifices 25 and 37 and orifices 26 and 38 are thereby placed in alignment. A roller 21 is rotatably mounted between portion 23 and portion 34 on a pintle 41 which is journaled in the orifices 26 and 38. A dog 42 is rotatably mounted between portion 23 and portion 34 on a pintle 43 which is journaled in orifices 25 and 37. Pintles 41 and 43 are maintained in place in any suitable manner as by swaging the terminals thereof or by affixing said pintles to the roller and dog respectively.
- 15 25. The dog 42 is provided with a working face 44 which is suitably scored or corrugated to provide an adequate gripping surface for engaging the cords 17 and 18 which are disposed between said face and roller 21. The circumferential movement of the dog is restricted in one direction by contact with the cords 17 and 18 and in the other direction by contact with an adjuster 45.

30 Adjuster 45 comprises a U shaped plate including a leg 46 and a leg 47 and an upturned flanged portion 48. The flange portion serves to impart rigidity thereto. Leg 47 is provided with a threaded orifice 49 which is penetrated by a machine screw 50.

35 A cord separator 51 is composed of a substantially right angle bent rod which is journaled at the outer end of the horizontal portion thereof in a pocket bearing formed by the two sides of indentation 28, the lower face of leg 36 and the upper face of bottom wall 15. The inner end of 40 the horizontal portion of separator 51 is journaled in a pocket bearing formed by the two sides of indentation 29, the lower face of leg 35 and the upper face of bottom wall 15. The vertical portion of separator 51 projects upwardly 45 through the widened portion 32 of indentation 29 and the orifice 39, which are aligned. The separator is put in place when the assembly frame 20 is placed within the casing 10. Frame 20 is maintained in position by a machine screw 52 which 50 penetrates an orifice (not shown) in the bottom wall 15 and threadedly engages the orifice 30 in base 24 and by the machine screw 50 which penetrates an orifice (not shown) in the bottom wall 15, the guideway 31 and terminates in 55 threaded engagement with the threaded orifice 49. An ordinary lock-washer (not shown) is used on screw 50 between the head of said screw and the outer under surface of bottom wall 15.

60 65. Operation

70 With the head-bar or head-piece casing 10 installed in the window frame in known manner, the screw 50 is loosened and using the screw head as an element which may be gripped either with a finger of the hand or a screw driver, the adjuster 45 is shifted longitudinally of the casing 10 until the dog 42 is in proper operating position, at which time the screw 50 is tightened. The 75 lock washer on screw 50 serves to minimize any

tendency of said screw to "walk" or shift in position as the same is tightened.

The proper operating position of dog 42 is determined by several factors, one of which is the weight of the slats and of the tilting tapes which are supported by the elevating and lowering cords 17 and 18. Another factor is the relative elasticity of said cords. Under the tension of the weight of slats and tapes the cords stretch out and the diameter thereof is reduced as illustrated 10 by the dot dash line 53 on Figure 2 of the accompanying drawing. When the cords 17 and 18 are in a condition of reduced diameter it is necessary that the dog 42 lie closer thereto as illustrated in said figure by the dash-dot line 54 15 which is accomplished by moving the adjuster 45 inwardly or to the right as seen in Figure 2.

When proper adjustment of the adjuster 45 and the dog 42 has been made, in order to regulate the height of the blind slats the procedure is 20 as follows: For raising the slats the exposed portion of the cords 17 and 18 is pulled downwardly and this in turn elevates the slats. During the elevation of the slats the dog 43 is relatively inactive and it is prevented from any wedging 25 action. When the slats have been raised the desired amount, the cords are released and the weight of the slats pulls the vertical portion of the cords upwardly. The cords then frictionally engage the working face 44 causing the dog 30 to turn upwardly and to wedge the cords between itself and the roller 21, thus checking the descent of the slats. For lowering the slats, the exposed vertical portion of the cords 17 and 18 is given a short downward tug, this causes the dog 35 42 to move downwardly and to thereby stop the wedging action thereof. The cords are then allowed to move upwardly but at an angle as indicated by the dash-double-dot lines 55 on Figure 2, so that the cords do not engage the 40 working face 44 sufficiently to actuate the dog 42.

It is possible by slightly changing the position of adjuster 45 outwardly or to the left as seen in Figure 2 to have the dog 42 wedge only when the cords are allowed to move upwardly at an angle 45 to the left of the vertical, and to have the dog 43 clear said cords when they are allowed to move upwardly in a vertical position. Such arrangement is subject to two objections. One, that very often the particular Venetian blind installation, as for example a corner window, does not permit moving the exposed portion of the cords outwardly of the blinds to lock the dog. Two, that upon accidentally releasing the said cords the blind slats will fall whereas in the arrangement set forth above the descent of the slats will be automatically checked.

50 As may be readily understood the diameter of the cords may be reduced by wear, or by non-elastic stretching, but the adjuster 45 may be 60 quickly and simply moved to compensate for any changes in operating condition.

The cord separator 51 operates to keep the cords 17 and 18 apart so that they do not become 65 twisted or tangled. Since the operating clearance between the dog 42 and the roller is set to accommodate only one cord, any tendency of one cord to ride upon or twist with the other would cause a jam, in turn requiring the casing 10 to be demounted for correction. The separator, because of the widened portion 32 in indentation 70 29 and orifice 39, is capable of limited rotation about a horizontal axis longitudinally of casing 10. This rotation coupled with the fact that the separator acts to keep the cords apart both be- 75

low and to one side of the roller, assures trouble-proof operation regardless of the direction or speed of travel of the cords.

It may thus be seen that I have provided a novel cord lock or brake adjuster and cord separator which is simple, economical, and effective in overcoming the disadvantages heretofore encountered.

The foregoing description has been made rather detailed for clearness of understanding only and no unnecessary limitations should be understood therefrom, but the appended claims should be construed as broadly as permissible in view of the prior art.

15 In the following claims the word "cord" is intended to mean any cord, string, or rope-like element.

Having thus described my invention, what I claim as new and desire to secure by Letters 20 Patent, is:

1. In a Venetian blind having slats; a cord adapted to move said slats, gravity operated movable means to stop the travel of said cord initially actuated by the engagement of the cord therewith adapted in one position thereof to grip said cord, means to regulate the clearance between said movable means of said cord when the movable means is in the second position thereof including a horizontally shiftable plate adapted 30 to engage said first means.

2. In a Venetian blind having slats; a cord adapted to move said slats, a gravity operated movable dog mounted on a stationary pivot to check the travel of said cord initially actuated by the engagement of the cord therewith, adapted in the engaging position thereof to grip said cord and in the disengaging position thereof to clear said cord, means to regulate the clearance between said dog and said cord when the dog is in 40 the disengaged position thereof.

3. In a Venetian blind having slats; a cord adapted to move said slats, a gravity operated pivotal dog initially actuated by the engagement of the cord therewith for checking the travel of said cord, adapted in the engaging position thereof to grip said cord and in the disengaging position thereof to clear said cord, means including a horizontally shiftable plate adapted to engage said dog to regulate the clearance between said dog and said cord when the dog is in the disengaged position thereof.

4. In a Venetian blind having slats, a cord adapted to move said slats, a stationary element over which the cord is adapted to travel, gravity operated movable means initially actuated by the engagement of the cord therewith, adapted in one position to stop the travel of said cord by compressing the cord between said movable means and said stationary element, and in a second position to clear and allow free travel to said cord, means to adjust the clearance between said movable means and said stationary element in the second position of the movable means.

5. In a Venetian blind having slats, a cord adapted to move said slats, a roller mounted on a stationary bearing over which said roller the cord is adapted to travel, gravity operated movable means initially actuated by the engagement of the cord therewith adapted in one position to stop the travel of said cord by compressing the cord between said movable means and said roller, and in a second position to clear and al-

low free travel to said cord, means to adjust the clearance between said movable means and said roller in the second position of the movable means.

6. In a Venetian blind having slats; a head 5 piece casing, a member stationary with relation to said casing, a cord adapted to move said slats, gravity operated movable means initially actuated by the movement of the cord therewith located within the casing and adapted to stop the 10 travel of said cord by compressing the cord against said stationary member, adjusting means within the casing to adjust the position of said first mentioned means with relation to said cord, means including a clamping screw accessible from outside the casing for moving said adjusting means, so that regulation of said adjusting means may be made without removing the head piece casing from a previously installed position. 15

7. In a Venetian blind having slats, an element, cords adapted to move said slats and disposed laterally next to each other, said cords simultaneously approaching said element in one direction and leaving said element in another 25 direction, separating means adjacent said element and adapted to maintain said cords apart in both said directions of travel.

8. In a Venetian blind having slats, a roller, 30 cords adapted to move said slats and disposed laterally next to each other, said cords simultaneously approaching said roller in one direction and leaving said roller in another direction, separating means adjacent said roller and adapted to maintain said cords apart in both of said 35 directions of travel.

9. In a Venetian blind having slats, an element, cords adapted to move said slats and disposed laterally next to each other, said cords simultaneously approaching said element in one 40 direction and leaving said element in another direction, L shaped separating means adjacent said element and adapted to maintain said cords apart in both said directions of travel.

10. In a Venetian blind having slats, a roller, 45 cords adapted to move said slats and disposed laterally next to each other, said cords simultaneously approaching said roller in one direction and leaving said roller in another direction, L shaped separating means adjacent said roller 50 and adapted to maintain said cords apart in both of said directions of travel.

11. In a Venetian blind having slats, an element, cords adapted to move said slats and disposed laterally next to each other, said cords 55 simultaneously approaching said element in one direction and leaving said element in another direction, L shaped separating means adapted for limited rotation about a substantially horizontal axis adjacent said element and adapted 60 to maintain said cords apart in both said directions of travel.

12. In a Venetian blind having slats, a roller, cords adapted to move said slats and disposed laterally next to each other, said cords simultaneously approaching said roller in one direction and leaving said roller in another direction, L shaped separating means adapted for limited rotation about a substantially horizontal axis adjacent said roller and adapted to maintain said 70 cords apart in both of said directions of travel.

JULIUS NISENSON.
